DETECTOR-OSCILLATOR CIRCUIT FOR
ULTRA HIGH FREQUENCY RECEIVERSGeorge W. Fyler, Stratford, Conn., assignor to
General Electric Company, a corporation of
New York

Application December 30, 1942, Serial No. 470,599

6 Claims. (Cl. 250—20)

1

My invention relates to circuits for ultra high frequency receivers and it has for its object to provide an improved frequency conversion circuit for such receivers.

My invention relates more particularly to detector-oscillator circuits for ultra high frequency waves in which transmission lines are used as part of the tuned circuits of the oscillator and detector. In such detector-oscillator circuits, it is desirable that all direct coupling between the ultra high frequency input circuit and the tank circuit of the local oscillator be avoided in order that no voltage of the oscillator frequency be induced in the antenna circuit of the receiver to cause currents of this frequency to flow in these circuits with consequent increased power drain on the oscillator, as well as undesired radiation of oscillator signals. It is desirable likewise that no voltage of the signal frequency be coupled into the oscillatory circuit of the oscillator to cause an undesired loading effect of the signal circuit with resultant loss in ultimate sensitivity.

It is an object of my invention to provide an improved converter-oscillator circuit for an ultra high frequency receiver in which a single set of transmission line conductors function as both the oscillatory circuit for the oscillator and the input circuit for the converter.

Another object of my invention is to provide an improved converter-oscillator circuit for a receiver for ultra high frequency radio waves in which a single transmission line is connected between the local oscillator and the converter and is adjustable by independent means to resonate at both the frequency of the local oscillator and the frequency of the input radio waves.

A further feature of my invention is the employment of a single pair of transmission line conductors in conjunction with a first electron discharge device as a source of local oscillations, the conductors being connected in parallel to supply in-phase oscillations to the control electrode of the first device, and in conjunction with a pair of electron discharge devices as a frequency conversion circuit, the pair of conductors being connected respectively to the control electrodes of the pair of devices to supply thereto in-phase oscillations from the local oscillator and out-of-phase signals from the radio frequency input circuits.

The features of my invention which I believe to be novel are set forth with particularity in the appended claims. My invention itself, however, both as to its organization and methods of operation, together with further objects and ad-

2

vantages thereof, may best be understood by reference to the following description taken in connection with the accompanying drawing, in which Fig. 1 is a partially diagrammatic perspective view representing the frequency conversion circuits for a receiver of the superheterodyne type embodying my invention; and Fig. 2 is a cross-sectional view taken along the line 2—2 of Fig. 1 looking in the direction of the arrows.

Referring to the drawing, I have shown a transmission line 10 to supply input signals from any desirable source, such as an antenna, to the input circuit of converter 11. Local oscillations are supplied by means of oscillator 12 and are mixed with the input radio frequency signals in converter 11 to provide, in the usual manner, currents in the anode circuit of the converter 11 of the desired intermediate frequencies, which currents appear in the primary winding of intermediate frequency transformer 13. The currents from the secondary of transformer 13 may be supplied by means of lead 14 to subsequent stages of the receiver which may comprise one or more amplifiers for the intermediate frequency currents, a detector, signal amplification means, and ultimately, a utilization means, such as a loud speaker. These latter portions of the receiver circuits may be of any desired type and are not shown in the drawing.

In my copending application, Serial No. 467-286, filed November 30, 1942, now Patent No. 2,416,577, entitled "Ultra high frequency conversion apparatus," and assigned to the assignee of the present invention, is disclosed an oscillator circuit in which an electron discharge device employs a series tuned circuit including a transmission line connected between its control grid and ground, the anode of the device being connected to ground at oscillation frequencies by a by-pass capacitor. The oscillator circuits 12 are similar to those described in said copending application and comprise an electron discharge device 15 having an anode 16, a cathode 17, and a control electrode 18. The discharge device 15 is mounted in the usual manner on a chassis 20, which acts as a conductive plane forming an equipotential surface fixed at ground potential for radio frequency currents. The control electrode 18 of device 15 is coupled, by means of capacitor 21 to a transmission line 22 comprising a pair of parallel rods or conductors 23 and 24 substantially equally spaced from plane 20 and a small distance thereabove, as shown at Fig. 2.

The line 22 and plane 20 thus form a tuned oscillatory or tank circuit in the circuit between

cathode 17 and control electrode 18, one side of said circuit being grounded for alternating currents. The line 22 is short-circuited by means of conductor 19 at the end connected to the control electrode 18 and is open-circuited at the other end, and a variable capacitor 25 is provided between the short-circuited end and the plane 20 for adjusting the electrical length of the oscillator transmission line oscillatory circuit. Resistor 26 is provided between cathode 17 and control electrode 18 to function as the usual grid leak resistor. The oscillator anode 16 is connected to ground through the small by-pass capacitor 21 to form an oscillator circuit as described in my above-mentioned copending application. Operating potential is supplied to the oscillator anode from the usual source, indicated on the drawing by the conductor bearing the legend +B and the negative terminal of which may be grounded. Anode 16 may be connected to this source through radio frequency choke coil 28 and inductance 29 is connected between cathode 17 and ground and serves as a cathode choke to control the uniformity of oscillations over the band through which the oscillator 12 operates. The value of inductance 29 is selected so that oscillator 12 may be tuned over its entire range of frequencies by adjustment of capacitor 25 and that an adequate and uniform voltage is supplied to the converter 11. If the value is too small, it may cause the oscillations to stop, whereas if it is too large, it may cause the oscillator to super-regenerate. In either case, uniformity of oscillation obviously is lost.

Radio frequency input signals being supplied from the antenna of the receiver over transmission line 10 are coupled to the transmission line 22 by means of the inductive loop 30, which loop preferably is balanced capacitively to ground or electrostatically shielded to prevent unbalanced coupling with the conductors of transmission line 22. By this means, any direct coupling between the oscillator circuit and the radio frequency input circuits is avoided so that the oscillator voltages are prevented from appearing in the antenna circuit to cause large currents of oscillation frequencies to appear in this circuit and cause radiation therefrom. A balanced inductive coupling likewise prevents radio frequency signal currents from appearing in the oscillator tank circuit, with corresponding loss in signal energy.

The open ends of the conductors of the transmission line 22 are connected respectively to the control electrodes 31 and 32 of the pair of electron discharge devices 33 and 34 in the circuit of the converter 11. The conductors 23 and 24 of line 22 are short-circuited at a point intermediate the open end and short-circuited end by means of an adjustable slider, or any other similar short-circuiting element, 35. By adjustment of the position of slider 35, the length of line 22 between slider 35 and the electrodes 31 and 32 may be adjusted for resonance at the frequency of the input radio frequency signals.

In the circuits of the converter 11, the anodes 36 and 37 of the devices 33 and 34 respectively are connected serially with the primary winding 40 of intermediate frequency transformer 13 to supply currents of intermediate frequency thereto. In order that currents of radio frequency do not appear in the primary winding 40, condenser 41 is connected between the anodes 36 and 37 and is selected to have a value such that, at the frequency of the input signals, it series resonates with the inductance of the leads connecting it to

the anodes, thus acting as a short-circuit for these signals and preventing their appearance in the primary winding. Operating potential for the anodes 36 and 37 is supplied from the usual potential source indicated in the drawing by the conductor bearing the legend +B and by-pass capacitor 43 is connected between the lower terminal of winding 40 and ground to prevent the flow of intermediate frequency currents to the potential source.

The cathodes 44 and 45 of the discharge devices 33 and 34 are connected together and are grounded to the chassis 20 by as short a lead as possible, the cathode preferably being connected to the tube base inside the respective tube and the base being grounded to the chassis in order to keep the degeneration in the input circuit of the converter 11 to a minimum value. At ultra high frequencies, degenerative loading of the grids of the devices 33 and 34 of the converter may occur due to the self-inductance of the cathode-to-cathode lead. Since this degeneration increases the input conductance of the converter and consequently reduces the signal potential at the grids, this lead is made as short as possible.

Resistor 47 is connected between slider 35 and ground to provide a path for unidirectional currents from grids 31 and 32 to ground and its value is so selected that with the correct oscillator voltage amplitude the resulting bias on grids 31 and 32 maintains these grids substantially at the cutoff voltages of the devices 33 and 34. Alternatively, a cathode biasing resistance and capacitance combination may be used.

Primary winding 40 and secondary winding 50 of intermediate frequency transformer 13 are shown as possessing an adjustable inductance determined by the position of the tuning cores or slugs 51 and 52. The positions of the slugs are adjusted so that the inductances of these windings are tuned to parallel resonance with the distributed capacity of the windings and circuit at the desired intermediate frequency. In this manner the winding 40 serves as an oscillatory circuit for the converter 11 tuned to the intermediate frequency and the winding 50 serves as a tuned input circuit for subsequent stages of the receiver.

In the operation of the frequency conversion circuit described, radio frequency input signals are inductively coupled to the input circuit of the converter 11 by means of the loop 30 located between conductors 23 and 24 between slider 35 and the control electrodes of the converter discharge devices. Slider 35 is so adjusted that the length of line 22 between the slider 35 and the control electrodes is tuned for resonance whereby the input signals are impressed upon the control electrodes 31 and 32 with opposite phase so that the line 22 serves as an out-of-phase push-pull input circuit line for the converter. The dotted lines 60 and 61 represent the voltage distribution along conductors 23 and 24 for voltages of the frequency of the input signals and illustrate the manner in which these voltages appear with maximum intensity and opposite phase upon the electrodes 31 and 32.

By means of variable capacitor 25, the electrical length of the connection between control electrode 18 of the oscillator and control electrodes 31 and 32 of the converter is adjusted for resonance at the frequency of the oscillations. The dotted line 62 represents the voltage distribution along the tuned transmission line including the conductors 23 and 24 for voltages of

the frequency of the local oscillator 12. As indicated, this tuned line is one-half wave length in length at the frequency of the local oscillator, so that the oscillator voltage appears with maximum intensity and in like phase relation upon the converter control electrodes 31 and 32. The inductance 29 makes it possible to tune the oscillator 12 over its entire range of frequency with good uniformity of the oscillator voltage supplied to the converter, the magnitude of the excitation voltage supplied to the converter being controlled by the magnitude of the voltage +B.

Due to the fact that the oscillator current is in-phase in conductors 23, 24 and the antenna coupling is effective only for out-of-phase currents in the same two conductors, no oscillator voltage is induced in the antenna circuit. Thus, by careful design of these circuits, there should be little or no coupling between the circuits. In this manner the same pair of conductors 23 and 24, since they are in the oscillatory circuit of the oscillator 12, form means for supplying oscillation voltages to the control electrodes 31 and 32 of the converter in-phase and because of their inductive coupling with the antenna circuit function as an out-of-phase push-pull transmission line for the radio frequency input signals. These circuits are tunable independently, the radio frequency input circuit being tuned by means of adjustment of slider 35 and the oscillatory circuit of the oscillator by means of the variable capacitor 25 connected between the oscillator grid circuit and ground. By proper selection of the value of resistance 47 and the potential applied to the anode 16, the oscillator may be made to produce automatically the correct converter bias.

The circuit of the converter 11 operates in the usual manner to produce in the anode circuits of the devices 33 and 34 currents having a frequency which is the difference between the frequency of the radio input signals and that of the oscillation signals on the local oscillator 12. The anodes of these devices are connected to the intermediate frequency transformer to impress intermediate frequency voltage across the primary of that transformer. Degenerative loading of the control electrodes of the converter, which degeneration normally is caused by self-inductance of the cathode leads and the grid to plate capacity of the devices, is reduced to a minimum by providing a short common cathode connection and by providing capacitor 41 to maintain the anodes of the devices substantially at the same potential for the radio signal frequency. By the symmetry of the circuit this must be zero radio frequency potential. This capacity series resonates with the inductance of the anode leads at the signal frequency so that the anode is at ground potential at this frequency. Therefore, an important object of the capacitor 41 is to prevent radio frequency signal voltage from appearing on the anode of the converter tubes thereby preventing any degenerative effect through the grid to plate capacity of these devices. The connections between the primary of the intermediate frequency transformer 13 and the anodes 36 and 37 are made as short as possible to keep at a minimum any linkage with the radio frequency and oscillation frequency fields existing in the vicinity, which linkage would increase undesirably the radio frequency potentials supplied to the intermediate frequency transformer.

While I have shown a particular embodiment of my invention, it will of course be understood that I do not wish to be limited thereto since

various modifications may be made, and I contemplate by the appended claims to cover any such modifications as fall within the true spirit and scope of my invention.

5. What I claim as new and desire to secure by Letters Patent of the United States is:

1. In an ultra high frequency receiving apparatus, a source of ultra high frequency signal waves, a local oscillator having a pair of input electrodes, a push-pull converter comprising a pair of electron discharge devices each having an anode, a cathode and a control electrode, a transmission line comprising a pair of parallel conductors, a conductive plane of fixed potential substantially equally spaced from said conductors, one end of each of said conductors being coupled to one of said input electrodes and said plane being connected to the other of said input electrodes, whereby said line and said plane form a tuned input circuit for said oscillator, and the other end of each of said conductors respectively being connected to one of said control electrodes, means inductively coupling said source of signal waves to said line, whereby said line forms an input circuit for said converter, means for tuning said oscillator input circuit thereby to impress oscillations of like phase on said control electrodes, and means for tuning said converter input circuit thereby to impress said waves on said control electrodes in opposite phase.

2. In a receiver for ultra high frequency waves, a push-pull converter having a pair of control electrodes, a transmission line connected in loop circuit between said control electrodes, means including said transmission line for impressing said ultra high frequency waves upon said control electrodes in opposite phase relation, a local oscillator including an input circuit, and means including said transmission line for tuning said input circuit to a desired frequency and impressing the generated oscillations upon said pair of control electrodes in like phase relation.

3. In a receiver for high frequency signal waves, a source of signal waves, an oscillator having a control electrode, a push-pull converter having a pair of control electrodes, and a transmission line comprising a pair of conductors, each of said conductors being connected at one of its ends to the control electrode of said oscillator and each of said conductors being connected at its other end to a respective one of said pair of control electrodes, adjustable means for tuning a portion of said transmission line to the frequency of said signal waves, means including said transmission line for impressing signal waves from said source upon said pair of control electrodes in opposite phase relation, and means for tuning said transmission line between the ends thereof to the frequency of said oscillations thereby to sustain said oscillations on said line and to impress said oscillations upon said pair of control electrodes in like phase relation.

4. In a high frequency radio receiver the combination of a source of signal waves, a source of local oscillations comprising an electron discharge device having a cathode and a control electrode, a resonant circuit connected between said cathode and control electrode and comprising a pair of parallel conductors each having one end coupled to said control electrode, a conductive plane of fixed potential in spaced relation with said conductors and connected to said cathode, and means connected between said conductors and said plane for tuning said resonant circuit to sustain said oscillations at a desired frequency, a push-pull

converter having a pair of control electrodes connected respectively to the other ends of said pair of conductors thereby to receive said oscillations in like phase relation, adjustable means for timing a portion of said line between said pair of control electrodes and an intermediate point on said line to the frequency of said waves, and means for inductively coupling said source of waves to said tuned portion of said line thereby to impress said waves upon said pair of control electrodes in opposite phase relation.

5. In an ultra high frequency receiving apparatus, a source of ultra high frequency signal waves, a transmission line comprising a pair of substantially parallel conductors connected together at one end and open-circuited at the other end, a source of local oscillations including an electron discharge device having a control electrode coupled to the connected ends of said conductors, a push-pull converter including a pair of electron discharge devices each having a control electrode coupled to one of said conductors at the open-circuited end of said transmission line, means for adjusting the electrical length of said line between the ends thereof for resonance at the frequency of said oscillations thereby to sustain said oscillations and to impress said oscillations upon said converter control electrodes in like phase relation, means for short-circuiting said conductors at a point intermediate the ends thereof thereby to adjust the electrical length of a portion of said line between said converter control electrodes and said short-circuiting means for resonance at the frequency of said waves, and means inductively coupling said source of waves to said portion of said line thereby to impress said waves upon said converter control electrodes in opposite phase relation.

6. In an ultra high frequency receiving apparatus a source of ultra high frequency signal waves, a source of local oscillations including a control electrode, a push-pull converter having a pair of control electrodes, a pair of substantially parallel Lecher wires each having one end connected to one of said pair of control electrodes and its other end connected to said local oscillator control electrode, means for short-circuiting said wires at a point spaced from each of said pair of control electrodes by a quarter wave length at the frequency of said signal waves, means inductively coupling said source of signal waves to said wires thereby to impress said waves upon said pair of control electrodes in opposing phase relation, and means for adjusting the electrical lengths of said wires between said pair of control electrodes and said oscillator control electrode to approximately one-half wave length at the frequency of said local oscillations thereby to maintain said oscillations and to impress said oscillations upon said pair of control electrodes in like phase relation.
